UNITED STATES PATENT OFFICE.

FRANCIS X. MUDD, OF CHICAGO, ILLINOIS.

BRACKET.

1,115,961.

Specification of Letters Patent.

Patented Nov. 3, 1914.

Application filed March 25, 1914. Serial No. 827,196.

To all whom it may concern:

Be it known that I, FRANCIS X. MUDD, a citizen of the United States, residing at Chicago, in the county of Cook and State of Illinois, have invented a new and useful Improvement in Brackets, of which the following is a specification.

My invention relates to an improvement in brackets, which I have devised for use, particularly, in poultry-cars of steel-construction, wherein the coop-doors on opposite sides of the central aisle have to be hinged to the channel-beam posts of the coop-structures and to latch themselves, when raised to close them, for holding them releasably in their closed condition.

In the accompanying drawings, Figure 1 is a general view representing a section taken lengthwise through the aisle-floor of a portion of a poultry-car, showing coops at one side of the aisle in elevation provided with doors hinged and fastened in their raised condition of closure by means of my improvement; Fig. 2 is an enlarged broken view showing in operative position one of the door hinging and latching brackets in elevation; Fig. 3 is a section on line 3, Fig. 2; Fig. 4 is a section on line 4, Fig. 2; Fig. 5 is a section on line 5, Fig. 4; Fig. 6 is a section on line 6, Fig. 2, and Fig. 7 is a broken view showing one of the ears of the bracket in section and the manner of releasably fastening therein a door-pivot.

In a poultry-car for which my improvement is particularly designed, the frame of the car is a steel structure involving channel-bar posts 7 at intervals along opposite sides of the central aisle 8 (Fig. 1), these posts marking the side-walls of the tiers of coops 35 and containing openings 9 for the troughs (not shown), one of which is located in line with each post-opening to be inserted through it into place and withdrawn through it into the aisle for emptying and 40 replenishing purposes. The front or aisle-member of the base of each horizontal row of the coops (except the lower horizontal row of the same) is an angle-bar 10, the horizontal web of which is cut away, as 45 shown in Fig. 4, at each post to embrace it between the sections, and the vertical web is riveted to the post.

For hinging the doors 11, which are of usual construction, each involving a frame 50 12 of general U-shape having elongated eyes 12^a in the ends of its legs between which ex-

tend spaced rods 13 braced by a central transversely-extending bar, I provide the bracket 14. This bracket comprises a flat plate containing a rivet-hole 15 near each end, and from the upper corners of the plate-ends project forwardly ears 16, 16 having countersunk outer faces and containing rectangular holes 17. In each ear-hole 17 fits a pin formed on its outer end with a 60 pintle 18 extending from a shoulder 19 to abut against the outer countersunk face of the ear with the rectangular portion of the pin fitting a hole 17, at the inner side of which that pin-portion contains a key-hole 20, beveled on its inner side to receive a 65 split headed key 21 having its shank correspondingly beveled to fit wedgingly in a hole 20.

A bracket 14 is riveted to a post 7 through 75 the rivet-holes 15, the rivets serving at the same time to fasten an angle-bar 10 to the post where it crosses the latter. One of these brackets is thus fastened in place to extend its pintles into position to have 80 mounted on them adjacent doors 11 at the eyes provided in the lower ends of the arms of their frames 12. To hinge an end of a door in this manner, the pin is inserted at its pintle-end into the eye provided in the door-frame, and its opposite end is then passed through a bracket-ear wherein it is releasably fastened by inserting a key 21 into the 85 pin-hole 20 to wedge the pin in place with its shoulder tight against the face of the 90 ear. In this way, each bracket serving to hinge the adjacent ends of each two doors, the doors are firmly hinged throughout the 95 coops in the car.

The brackets are formed as described only 95 for the doors of each lowermost horizontal row of the coops. For the doors above that row each bracket is provided with legs 22 depending from the end-portions of the bracket-plate, these legs being slightly offset, 100 as shown at 23 in Fig. 3, to fit over the vertical web of an angle-bar 10 crossed by them; and each leg is provided on the lower end of its face with a hook or catch 24 to be engaged by the frame of a door when raised 105 for releasably holding the latter in its closed position. Above each catch a stop 25 projects from the face of the bracket-leg, whereby by jarring of the car, tending to unlatch the doors, will ride their frames 12 up inclined 110 sections 24^a of the hooks 24, of which one is shown in Fig. 3, and underneath the stops

25 to be prevented by the latter from becoming unlatched. Sufficient play for the pintles is afforded by the elongated eyes 12^a engaging them to permit the door-frames, in 5 closing the doors, to ride over the hook-ends of the catches 24 and drop to seat on the shank-portions of the latter.

As will thus be seen, the bracket, for fastening which to a post 7 are employed the 10 same rivets required to fasten an angle-bar thereto, affords very desirable means for 15 both stably hinging the coop-doors and holding them releasably in their closed condition; and the bracket-pins enable the operations of hinging the doors in place and removing them to be performed expeditiously with great facility.

What I claim as new and desire to secure by Letters Patent is:—

20 1. A door-hinging bracket for poultry-car coop-doors, comprising a plate adapted to be secured to an aisle-post in the car and provided with a pair of perforate ears, angular pins fitting the ear-perforations and 25 having pintles formed on their outwardly-projecting ends and intermediate shoulders to bear against the outer faces of said ears, and means on the outer ends of said pins for removably fastening them in place, the pintles on each bracket serving as hinge-members for hinging two adjacent coop-doors on 30 said post.

2. A door-hinging bracket for the coop-doors of a poultry-car, comprising a plate 35 adapted to be secured to an aisle-post in the

car and provided with perforate ears having countersunk outer faces, angular pins fitting the ear-perforations and having key-holes in their inner ends, pintles on their outwardly-projecting ends and intermediate shoulders 40 to bear against the outer faces of said ears, and keys fitting said holes for fastening the pins in place, the pintles on each bracket serving as hinge-members for hinging two adjacent coop-doors on said post. 45

3. A door-hinging bracket for poultry-car coop-doors, comprising a plate adapted to be secured to an aisle-post in the car and provided with pintle-forming pins serving as hinge-members for hinging two adjacent 50 coop-doors on said post, and legs depending from the plate, provided with hooks for engagement with doors below the bracket to hold them when raised for closure, and with door-stops above the hooks. 55

4. A door-hinging bracket for the coop-doors of a poultry-car, comprising a plate adapted to be secured to an aisle-post in the car and provided with pintle-forming pins serving as hinge-members for hinging two adjacent coop-doors on said post, and legs depending from the plate, provided with hooks for engagement with doors below the bracket to hold them when raised for closure 60 and with stops above the hooks, said hooks 65 having upwardly-inclined sections.

FRANCIS X. MUDD.
